Ses. 904

Sam'l. D. Nose, of Albany, N.Y.
Letters Patent No. 904. Dated July 7, 1857.

The schedule referred to in the Letters Patent, and making part of the same.

To all whom it may concern: Be it known that I, Sam'l.

Des. 904

D. Nose, of Albany, County of Albany and State of New York, have invented or produced a new design for ornamenting stoves, and I do hereby declare that the following is a full and exact description of the same, reference being had to the drawings annexed to and making part of this specification.

The nature of my invention will not admit of an intelligible description in words, being made up of a combination of mouldings and figures, as shown in the accompanying diagrams.

The drawings, Figs: 1 & 2, represent the new design I have produced, and are a fac-simile of my invention.

I do not claim any separate moulding or figure in the configuration.

What I claim as my invention and desire to secure by Letters Patent is the arrangement and combination of the various figures and mouldings, the whole forming an ornament -

A. I. M. al design for stoves, as herein described.
